W. A. BERNHARD,
FOLDING CHAIR,
APPLICATION FILED OCT. 13, 1916.

1,241,907.

Patented Oct. 2, 1917.

UNITED STATES PATENT OFFICE.

WILLIAM A. BERNHARD, OF WOODHAVEN, NEW YORK.

FOLDING CHAIR.

1,241,907.

Specification of Letters Patent.

Patented Oct. 2, 1917.

Application filed October 13, 1916. Serial No. 125,456.

To all whom it may concern:

Be it known that I, WILLIAM A. BERNHARD, a citizen of the United States, residing at Woodhaven, in the county of Queens and 5 State of New York, have invented new and useful Improvements in Folding Chairs, of which the following is a specification.

This invention relates to folding chairs and has for its principal object the provision of a device of this character which can be folded perfectly flat into a relatively compact package for shipment or storage; one which will be simple of construction and reliable in use; one which will 15 be designed so that it may be converted into a stool or arranged in the form of a table if desired.

Another object of the invention is the provision of a chair having a seat provided 20 with a swinging back, the elements of the latter being associated with the elements of the seat so that they all constitute a uniform or uninterrupted top surface when the device is arranged as a stool or table.

25 In the drawings:—

Figure 1 is a perspective view of the device.

Fig. 2 is a perspective view thereof showing the same folded.

30 Fig. 3 is a side view of the same.

Fig. 4 is a bottom plan view thereof.

The device consists of a main seat 1, which is preferably made up from a plurality of spaced bars or slats 2, the forward ends of 35 which overlie and have permanent connection with a transverse bar 3. Adjacent to the rear ends, said slats overlie and have permanent connection with a transverse bar 4. Brackets 5, upon the bar 3, serve as 40 pivotal supports for the legs 6—6. These legs are connected by a transverse round 7, whereby they are given stability. Similar legs 8—8, are pivotally connected with brackets 9—9, which extend from the bar 45 4, and these legs are connected also by a round 7' to give them stability. Attention is invited to the fact that the brackets 5 carrying the front legs 6 are spaced farther from each other than the brackets 9 carrying 50 the rear legs 8, whereby the former pass entirely outside of the rear legs 6 when the device is folded as seen in Fig. 4. Attention is also invited to the fact that the legs are of such length that when folded upward 55 they lie flat against the lower side of the seat, which follows from the spacing of the

bars 3 and 4 a greater distance from each other than the length of the legs.

Toggle lever braces 10 connect the front legs 6 with the rear legs 8, and each brace 60 comprises a metallic link 11 pivoted at its rear end to a rear leg near the upper end of the latter, and a second metallic link 13 pivoted at its front end at 14 to a front leg 6 near the lower end of the latter. The 65 meeting ends of these links are connected by an intermediate pivot 12, adjacent which the upper edge of one link, as 11, is provided with a recess 15, while the other link, at 13, is continued beyond the pivot and deflected 70 at its extremity into a stop lug 16 adapted to engage said recess when the links are in alignment as seen in Fig. 3. Therefore the toggle can not be broken by pressing downward on its intermediate pivot at this time, 75 but by inverting the entire structure and applying pressure at the bottom of the toggle, the same can be broken and the front and rear legs are then free to be swung against the seat 1, and against the under 80 side thereof as shown in Fig. 4. The legs 8—8, are provided with notches 8', to receive the round 7, of the legs 6—6, when the latter are folded against the under side 85 of the seat 1.

The back 17 is likewise composed of spaced slats 18 alternated with and intervening between the rear ends of the seat slats 2 and connected with each other across both extremities by strips 19. The back is 90 pivoted to the seat by a through-bolt 20 which passes through all slats at a point sufficiently in rear of the transverse bar 4 to permit the back to incline a little to the rear when it stands upright, at which time 95 the lower extremities of the slats 18 rest against said bar 4 as seen in Fig. 3. The distance between the two strips 19 is such that when the back is folded these strips pass the extremities of the seat slats and afford a neat finish for both the front and rear edge of the structure. This construction is such that the back may be adjusted to a horizontal position in order that the upper 100 surfaces of its slats will come flush with the 105 corresponding surfaces of the slats 2.

There is then a nice continuity of surfaces giving an uninterrupted upper face to the seat structure and the device is then capable of being used either as a table or stool. 110

When the device is in the position shown in Fig. 1, the combined seat section and back

rest is extended at an inclined angle to the horizontal surface of the section 1, in order that the back of the person when seated will be comfortably accommodated in a reclining position. The device is light, strong and durable and is capable of being quickly transported and set up or knocked down as the occasion demands. It is exceedingly useful for campers, tourists, and the like in view of its compactness, as will be understood.

When the section 17, is adjusted to the position shown in Fig. 2, the strips 19—19, are extended over the ends of the bars 2, so as to give an attractive and ornamental appearance to the seat. When the section 17, is adjusted to the inclined position shown in Figs. 1 and 3, the adjacent lower ends of the bars 18, come in contact with the bar 4, and the latter thus forms a stop to limit the tilting movement of said section 17.

The device can also be used to advantage

in canoes, boats or like places and at such time the legs 6 and 8, can be folded against the under side of the bars 2, and the back 25 rest adjusted to the position shown in Fig. 1.

What is claimed as new is:—

In a folding chair, the combination with a seat made up of spaced parallel slats and transverse front and rear bars upon which 30 the slats are secured, brackets on both bars projecting inwardly beneath the slats, and folding legs carried by said brackets; of a back made of parallel spaced slats of a length equal to those of the seat-slats and alternated therewith, a pivot bolt through all slats at a point in rear of the rearmost transverse bar and equi-distant from the rear ends of the seat-slats and the lower ends of the back-slats, and transverse strips 40 secured across the extremities of the back-slats, all as and for the purpose described.

In testimony whereof I affix my signature.
WILLIAM A. BERNHARD.
